Inventor
Earle C. Haas,

By Clarence A. O'Brien
Attorney

UNITED STATES PATENT OFFICE.

EARLE C. HAAS, OF WRAY, COLORADO.

MEDICAL-POWDER APPLICATOR.

Application filed February 24, 1927. Serial No. 170,690.

This invention relates to new and useful improvements in devices for applying medicinal powder to different body orifices, and has for its primary object to provide a 5 relatively simple and easily operable device wherein the powder may be delivered to predetermined point within the orifice and thence properly discharged.

A further and important object of the 10 invention is to provide means whereby powder cartridges may be injected into the device and thence delivered to the infected parts, after which the powder may be forcibly projected from the cartridge. By reason of the provision of such a cartridge, the 15 medicinal powder may be conveniently sold to the trade, and such powder may be readily disposed within the applicator without any liability of the same spilling or being 20 projected from the device until such is the intention of the using party or attending physician.

With the foregoing and other objects in view as the nature of the invention will be 25 better understood, the same comprises the novel form, combination and arrangement of parts hereinafter more fully described, shown in the accompanying drawing and claimed.

30 In the drawing wherein like reference characters indicate corresponding parts throughout the several views:

Figure 1 is a detail longitudinal section through my improved medical powder applicator, a powder cartridge being shown as arranged therein and the powder being disclosed as being projected therefrom, and

40 Figure 2 is a perspective of a powder cartridge that is preferably used in carrying out the present invention.

Now having particular reference to the drawing, my novel applicator consists of a relatively elongated cylinder of small diameter, and constructed of any suitable material. The inner end of the same being formed with an outwardly extending circumferential flange 6 so as to provide a finger attachment at this end of the cylinder.

50 The opposite end of the cylinder is formed with an internal circumferential lip 7, while slidably arranged within this cylinder is an elongated piston 8, the inner end of which is provided with a reduced stem 9 having 55 a pin point 10 upon the inner end thereof.

In carrying out the present invention, there is provided a heavy paper or cardboard cartridge 11 of cylindrical formation and being of a diameter such as to permit of the free movement of the same within the cylinder 5. The top wall of this cartridge is composed of thin paper 12 having cross perforations 13 therein in order that this paper may be easily broken when pressure is applied to the medicinal powder 14 therein. 60 Arranged within the lower end of the cylindrical cartridge is a plunger-like wad 15 that will be impaled upon the pin 10 of the reduced stem 9 of said piston 8 when the same is forced thereagainst, it being obvious 65 that the reduced stem 9 is for the purpose of permitting the same to pass into the body of the cartridge during the projection of the powder therefrom. Obviously after the pin 10 has been forced through the wad 15 a 70 further pressure upon the outer end of the piston 8 will cause this wad to so act against the powder 14 within the cartridge as to cause the breaking of the wall 12 and the resultant projection of the powder therefrom 75 as suggested in Figure 1.

For purposes of facilitating the proper actuation of the piston 8 the outer end thereof may be and preferably is formed with a disc-like head 16 to be engaged by the palm 80 of the hand directly beneath the thumb thereof.

It will thus be seen that I have provided a highly novel, simple and inexpensive medicinal powder applicator that is well adapted 90 for all the purposes heretofore designated, and even though I have herein shown and described the invention as consisting of certain detail structural elements it is nevertheless to be understood that some changes may 95 be made therein without affecting the spirit and scope of the appended claims.

Having thus described the invention, what I claim is:

1. In a medical powder applicator, where- 100 in the powder is disposed within a cartridge having a disruptible closure at one end and a wadded closure at its opposite end, a tubular cylinder for receiving said cartridge, means in the forward end of the cylinder to 105 prevent the passage of the cartridge there- through, a piston slidable within the cylinder, and means at the inner end of the pis- 110 ton for engaging said wad and for engage- ment within the cartridge when the piston

is forced into the cylinder so as to force the wad inwardly causing the breaking of the disruptible end of said cartridge.

2. In a medical powder applicator for use in applying powder to affected body within a cylindrical cartridge, the outer end within a cylindrical cartridge, the outer end thereof being closed by a disruptible material, and the inner end thereof being closed by a wad, a cylinder for receiving said cartridge, means at the forward end of the cylinder to prevent the passage of the cartridge therethrough, and a piston slidably mounted within the cylinder and adapted to engage the wad of the cartridge to force the same inwardly of the cylindrical shell for breaking said disruptible closure.
3. In a medical powder applicator for use in applying powder to affected body orifices

wherein the powder is arranged within a cylindrical cartridge, the outer end thereof being closed by a disruptible material, and the inner end thereof being closed by a wad, a cylinder for receiving said cartridge, means at the forward end of the cylinder to prevent the passage of the cartridge therethrough, a piston slidably within the cylinder and having a reduced inner end for engagement within the cartridge shell and for engagement with the cartridge wad whereby a pressure of the piston will cause the inward movement of the wad to break the disruptible closure so that a further movement of the piston will discharge the powder from the cartridge.

In testimony whereof I affix my signature.

EARLE C. HAAS.
